UNITED STATES PATENT OFFICE.

CHARLES E. ADAMSON, OF BUFFALO, NEW YORK, ASSIGNOR TO KNAPP HUSKER COMPANY, OF BALTIMORE, MARYLAND, A CORPORATION OF MARYLAND.

DUPPLICATING OR PRINTING MACHINE.

1,155,696.

Specification of Letters Patent.

Patented Oct. 5, 1915.

Application filed September 24, 1909. Serial No. 512,816.

To all whom it may concern:

Be it known that I, CHARLES E. ADAMSON, a citizen of the United States, residing at Buffalo, in the county of Erie and State 5 of New York, have invented certain new and useful Improvements in Duplicating or Printing Machines, of which the following is a specification.

My invention relates to improvements in 10 printing or duplicating machines, particularly of that type devised for printing imitation typewritten letters.

One of the objects of my invention is the production of a machine of this character 15 which can be actuated either manually or by means of a suitable motor, and with which, when driven by power, a high printing capacity is obtained.

Another object is the provision of paper 20 feeding-mechanism which will feed the paper in quick succession to the type-form with exact register, so that the printed sheets can be run through the press a second time for insertion of printed matter in 25 different color, with assurance that it will register perfectly on all sheets with the matter previously printed, and to so devise said mechanism that when feeding the sheets onto the type-form, they will not "float" in 30 the air and land in different positions on the type-form.

Another object of my invention is the employment of a movable paper-support or positioner onto which the sheets of paper to be 35 printed are laid and which is automatically adjustable longitudinally upon actuation of the machine to cause the feeding-mechanism to grip the successive sheets laid thereon without the slightest variation.

Another object of the invention is the provision of laterally-adjustable means on said paper-support or positioner adapted to position the sheets of paper so that when they 40 are fed forward by the feeding-mechanism they will always be exactly positioned with reference to the sides of the type-form.

Other objects are to provide a reciprocating carrier equipped with an impression-member, paper feeding - mechanism and paper delivery-mechanism; to provide an 45 initial rotating operating-member to be rotated either manually or by means of power, and to interpose between said operating-member and said carrier, transmission-mechanism converting the rotary motion to

reciprocating motion; to provide means for changing the length of the reciprocatory strokes of said carrier; to equip the machine with means to throw the impression-member out of printing-position; to provide means 60 to throw the paper feeding-mechanism out of feeding position; and to otherwise improve on machines of the character mentioned.

To these ends the invention consists in the 65 arrangement and combination of devices and in the construction, arrangement, and combination of parts to be hereinafter described and particularly pointed out in the subjoined claims.

In the drawings,—Figures 1 and 2 are side elevations of my improved machine viewed from opposite sides. Fig. 3 is a plan view of the same. Fig. 4 is a central longitudinal section, showing the reciprocating carrier in 75 its foremost position. Fig. 5 is a transverse section taken on line *p*—*p*, Fig. 3. Fig. 6 is an enlarged transverse section through the upper portion of the machine, taken on line *r*—*r*, Fig. 3; the paper-shaft and paper-positioner being omitted. Fig. 7 is a detached perspective view of the oscillating gripper forming part of the paper feeding-mechanism. Fig. 8 is a detached perspective view of the carrier with the attached ends 80 of the driving-chain. Fig. 9 is an enlarged longitudinal section taken on line *s*—*s*, Fig. 3, looking in the direction of the arrow crossing said line, the carrier being at the beginning of its return or rearward movement. Fig. 10 is an enlarged longitudinal section taken on line *t*—*t*, Fig. 3, looking in the direction of the arrow crossing said line, the carrier being at the end of its forward 85 movement. Fig. 11 is an enlarged vertical section through the slide-head forming part of the throw-off device and the adjacent portion of the frame, the section being taken on line *u*—*u*, Fig. 1. Figs. 12, 13 and 14 are enlarged longitudinal sections taken on line *v*—*v*, Fig. 3; the carrier being shown in different positions. Figs. 15, 16, and 17 are enlarged longitudinal sections taken on line *w*—*w*, Fig. 3, looking in the direction of the arrow crossing said line and showing the 90 different positions of the parts forming the paper feeding-mechanism. Figs. 18 and 19 are sections on an enlarged scale taken on line *x*—*x*, Fig. 3, showing different positions of the gripping roller forming part of the 95 100 105 110

paper delivery-mechanism. Fig. 20 is a section on an enlarged scale, taken on line $z-z$, Fig. 3. Fig. 21 is an enlarged section taken on line $y-y$, Fig. 3, the paper shaft 5 being omitted. Fig. 22 is a detached perspective view of the paper-support or positioner. Fig. 23 is a detached perspective view of the trip-device coöperating with the paper feeding-mechanism. Fig. 24 is an enlarged transverse section through the upper 10 part of the machine taken on line $o-o$, Fig. 3. Fig. 25 is a perspective view of the paper-support upon which rests the rear end of the sheet of paper to be printed. Fig. 15 26 is a section taken on line $n-n$, Fig. 6. Fig. 27 is a sectional plan view of a portion of the rear member of the carrier and a portion of the frame or body of the machine at the rear end thereof.

20 Referring now to the drawings in detail, like numerals of reference refer to like parts in the several figures.

The reference numeral 1 designates a support of any suitable construction, upon which the machine is placed. This support has a top 2 slidable in grooves 3 in the sides of said support.

A paper-receiver 4 is provided which is hinged between its ends to the rear end of the ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ 55 By pivotally securing the paper-receiver to the slidable top 2 of said support, it can be adjusted lengthwise on the support and when the machine is not in operation, the retaining-rod 5 may be disengaged from the top 2 to permit the inner end of said receiver to be swung against the top, and the latter 60 may then be forced forward to bring the receiver underneath the machine proper.

9 designates the frame or body of the machine which comprises sides 10 having legs 11 and being connected by a flat bed 12 somewhat shorter than the sides and pro-

vided with a pair of longitudinal grooves 13, one being in close proximity to each side. Within the grooves 13, yieldingly-supported tracks 14 are located, each track having counterbored openings 15 at intervals along its length, through which are loosely passed screws 16 that take into the bed 12 and have their heads located in the counterbored portions of said openings. Surrounding said screws between the tracks and the bed are coil-springs 17 serving to hold the tracks elevated and yield under pressure. 70 75

The sides 10 extend above the bed 12 and at their upper edges have inwardly-directed flanges 18, preferably formed by securing plates to the edges and arranging them to overhang the inner faces of said sides. These flanges may be formed integrally with said sides and are therefore to be considered parts of the sides of said frame or body. By providing the sides 10 with overhanging flanges, guide-grooves 18^a are formed between them and the tracks 14. 80 35

The bed 12 is provided with two longitudinal depressions 19 in which are secured 90 retainers 20 in the form of strips of metal bent into angle-shape transversely; one of the members of each retainer being embedded in the coöperating depression 19 and the other being directed vertically to rise 95 from the bed. The front end of each strip is bent upward, as at 21, to provide stops for a chase 22 laid upon the bed 12 and having a type-form, cut, or other matter 23 secured therein and from which an imprint is 100 to be taken.

Between one of the retainers 20 and the chase 22, a friction-strip 24 is interposed and between the opposite retainer and the chase, a trip-rail 25 is fastened. 105

Arranged between the retainer-strips 20 and the tracks 14 are trip-rails 26, one at least of which is longitudinally movable and has a depending pin or stud 27 which extends through a longitudinally-disposed slot 110 28 and enters an opening in a shifting-bar 29 fastened to the underside of the bed 12. Said shifting-bar extends forward and has a slide-head 30 secured thereto, which is preferably formed of a bar of metal bent at right-angles near opposite ends to provide a vertical intermediate member 31, a short arm 32 at the upper end of said intermediate member extending over the adjacent flange 18 and a long arm 33 extending underneath the bed 12 and connected to the shifting-bar 29. An upstanding handle 34 is provided for said slide-head to render the mechanism 115 120 convenient to operate.

A bearing-block 35 is secured to the underside of the short-arm 32 of the slide head and slides in contact with the upper side of the adjacent flange 18, and for a purpose to appear hereinafter, said bearing-block is extended, as at 36, Figs. 12 to 14. 130

37 designates a traveling carrier on which are mounted the impression-member, the paper feeding-mechanism, and the paper delivery-mechanism. Said carrier comprises 5 a front member 38 and a rear member 39 connected by rods 40. The front member comprises sides 41 connected by a cross-bar 42, and two pairs of bearing-boxes 43, 44, held to said sides. The rear member 39

10 comprises sides 45 and a cross-bar 46.

A transversely-disposed impression-roller 47 is positioned underneath the cross-bar 42 and is loosely held on a shaft having eccentrically-arranged journals 48 which are 15 journaled in the bearing-boxes 43. Adjusting-screws 49 are passed through the ends of said cross-bar and enter the bearing-boxes 43 so that upon turning said screws, said boxes will be raised or lowered, as the case may be, 20 and the impression-roller adjusted with reference to the printing surface. Suitable jam-nuts 50 are threaded onto said adjusting-screws and impinge against the upper face of the cross-bar 42 to retain the impression-roller in adjusted position.

Secured to the shaft or pintle of the impression-roller at opposite ends of the latter, are trip-arms 51, 52; each adapted to have its end tapered and to travel in contact with 30 the trip-rails 26 during certain portions of the movements of the carrier. The carrier has preferably a reciprocating movement and when the machine is in operation for printing, said trip-arms ride over the opposite ends of said rails. Said trip-arms are somewhat longer than the space between the upper faces of the trip-rails 26 and the true axis of the impression-roller when the latter is directly over said rails; consequently, the 35 said arms are inclined in opposite directions during opposite movements of the carrier and have a dragging action over said rails. The trip-rails are of a length to cause said trip-arms to ride over their ends and secured 40 to said arms are curved springs 53 which bear against the underside of the cross-bar 42 and act to hold the said trip-arms in contact with said rails and to cause said arms to assume almost a vertical position 45 after having passed over the ends of said rails. This brings the extremities of the trip-arms in a plane beneath the surfaces of said trip-rail and when said arms are again drawn over the trip-rails they are caused to 50 incline in an opposite direction. The trip-arms are therefore inclined rearward during the forward movement of the carrier and forward during the rearward movement thereof and this change of inclination is 55 effected at the ends of the opposite carrier movements, and as the said arms are fastened to the shaft or spindle of the impression-roller and the latter is loosely on the shaft and eccentrically journaled, said shaft 60 is caused to rock and is so positioned that it

moves the impression roller into and out of printing-position.

The springs 53 secured to the trip-arms 51, 52, are oppositely disposed, as shown in Figs. 9 and 10, so that one spring acts to 70 force said arms in one direction and the other to force them in the opposite direction, and as both arms are rigidly secured to the shaft or spindle of the impression-roller, the action of one arm is imparted to the 75 other. It is to be noted that one of said springs is inactive when the other is active, thus preventing counteraction and assuring a positive trip at all times.

As stated, one of the trip-rails 26 is connected to the slide-head 30 and therefore movable with it so that it may be moved lengthwise on the bed 12. This is done to bring the rear end of said rail beyond the rearmost point which the co-acting trip-arm 51 will assume, consequently said arm cannot move over the end of said rail when the latter is moved rearward, and when said rail is thus positioned, the trip-arms retain their forward inclination and are forced 80 over and in contact with said rail without change of position. By this means, the impression-roller is held elevated or out of printing position, thus permitting the machine to run idle so as to enable the operator 85 to remove the printed paper from the paper-receiver, adjust the machine for printing different size paper, stack up a further supply of paper, and attend to such other matters as are necessarily required when operating a machine of this character.

The carrier 37 is reciprocated by means of two chains 54 having opposite ends fastened to the sides 41 of the front member 38 thereof, as best shown in Fig. 8. These 105 chains are driven by chain-wheels 55 secured to a transverse-shaft 56 journaled in the sides of the machine at or near their front ends, said chains passing around said wheels and around grooved wheels 57 rotatable on 110 stub-axles 58 secured to said sides near their rear ends. Shaft 56 projects through one side of the machine and has a gear-wheel 59 secured thereto which is rotated intermittently in opposite directions by a gear rack 115 60 having a slide-block 61 at one end which is guided for reciprocating movement between two guide-bars 62, 63, secured to the side of the frame or body.

A master-shaft 64 is journaled in the sides 120 of said frame or body, preferably at a point midway between its ends, said shaft being of a length to protrude from opposite sides of said frame. To one end of said shaft, a comparatively heavy operating or driving-wheel 65 is secured which has a handle 66 a distance from its axis so as to obtain the necessary leverage to easily operate the machine. A wheel of the type mentioned acts as a fly-wheel and its momentum assures a 130

quick reverse action of the several parts without added exertion on the part of the operator. Said operating or driving-wheel has a circumferential groove 67 to receive a belt when it is desired to operate the machine by power. To the opposite end of said master-shaft, a pinion 68 is secured which is in mesh with a gear-wheel 69 secured to a shaft 70 journaled in the side of the frame or body.

Pivotedly connected at one end to said gear-wheel 69 is a pitman 70^a having its opposite end pivotedly connected to the slide-block 61 so that when said wheel is rotated, said slide-block and its gear-rack 60 are reciprocated and cause rotation of the shaft 56, and the consequent reciprocation of the carrier.

When it is desired to print medium size forms, the pivot-screw connecting the pitman 70^a with the gear-wheel 69, may be passed through a pivot-hole 71 in the pitman, and when short forms or postal cards are to be printed, said pivot-screw may be passed through a pivot-hole 72 in said pitman. By regulating the movement of the carrier to the size of the form to be printed, a given number of sheets can be printed in a much shorter period of time and considerable wear on the machine will be eliminated by dispensing with idle movements.

Held to the frame or body of the machine in any suitable manner is a paper shelf 73, onto which a stack of paper 74 to be printed is piled. This shelf is preferably positioned in a plane above the frame or bed and at its rear end it has an upstanding wall 75, while at its outer longitudinal edge it has an upwardly and inwardly-directed wall 76. The sheets of paper are piled on said shelf with contiguous edges against said walls and by slanting the longitudinal wall 76 inward, the sheets are arranged so that the top sheet can easily be removed.

45 77 designates a paper-support or positioner which is adjustably held at the front end of the machine in a plane above the printing surface and between the sides of the frame or body. Said support or positioner comprises a flat bottom 78, side walls 79 provided at their rear portions with grooves 80, and a front wall 81. The flanges 18 at the upper ends of the sides of the frame 9 fit into said grooves so that said support or positioner may be adjusted lengthwise on said frame. The bottom 78 has a pair of transverse slots 82 adjacent one side wall through which curved upwardly-directed gage-arms 83 are passed, said arms having collars 84 near their lower ends which rest upon said bottom and their lower ends are threaded for application thereto of securing-nuts 85. A longitudinal gage-bar 86 is located near the opposite side wall and it has a pair of threaded studs 87 which ex-

tend through transverse slots 88 in said bottom and have nuts 89 applied thereto. The gage-arms 83 and the gage-bar 86 are therefore movable transversely so as to permit their being adjusted to gage sheets of paper 70 of various widths. The gage-arms 83 have their upper end curved toward the gage-bar 86 so that when placing a sheet of paper upon the support or positioner, one longitudinal edge thereof is placed against said 75 gage-bar and when releasing the sheet, it gravitates with the opposite edge traveling along the curved arms. The sheet is thus placed on the bottom of the support or positioner with opposite longitudinal edges 80 against said arms and bar.

The paper feeding-mechanism comprises a roller 90 and a gripper 91. Said roller has eccentric journals 92 journaled in the bearing boxes 44, and it has also, by preference, 85 a sectional contact surface formed by short separated contact members 93. At one end, said eccentrically-mounted roller has a trip-arm 94 secured thereto which rides over and in contact with the trip-rail 25 and at its 90 other end it has a torsion spring 95 surrounding its spindle. One end of said spring is secured to the roller and its other end to the side of the carrier. Said trip-arm is inclined rearward and held in contact with said rail by the spring 95, which at all times exerts its force to rock said roller, but as the trip arm is limited in its downward movement by said trip-rail, it prevents 100 rocking of said roller until after said trip-arm rides over the rear end of said trip-rail, at which time said trip-arm is free to move in a forward direction and cannot then act to check the action of said spring. During the forward movement of the carrier, said trip-arm rides over the end of said trip-rail and is caused to swing rearward so that the roller is rocked in an opposite direction and the spring 95 is placed under 105 tension. The trip-arm riding in contact with the upper face of said rail, retains the roller and the spring in position until the carrier again approaches the end of the rearward movement. It is to be noted that the trip-arm 94 does not ride over the front 110 end of the trip-rail 25 and consequently oscillates or rocks only at the end of its rearward movement.

The gripper is best shown in Fig. 7, and it comprises a bar 96 having a forwardly-directed gripping-ledge 97 which lies in a plane beneath the roller 90. Said gripper has two upwardly-directed arms 98 which are slotted, as at 99, and passing through said slots and taking into an oscillating yoke 100 are screws 101. Said slots and screws permit the gripper to be adjusted on said yoke for the purpose of bringing the gripping-ledge 97 in proper relation to said roller. Said yoke comprises a cross-bar 102 130

lying in front of the cross-bar 42 of the carrier and rearwardly extending arms 103 pivotally secured to the sides 41 of said carrier, as at 104. One of said arms is extended 5 beyond its pivotal point and at its rear end has a laterally directed toe or rider 105 which is adapted, at certain points in the movement of said carrier to engage a trip-device 106. Said toe or rider preferably has 10 its upper and lower face made convex, for a purpose to appear hereinafter. Said trip-device is located on one of the flanges 18 at the upper edge of the frame or body directly in rear of the slide-head 30, and it 15 comprises a spring tongue or arm 107 inclined rearward and having its rear end normally in contact with said flange and its front end elevated and separated from said flange by an intervening space 108, and a 20 suitable support 109 fastened to said flange to hold said arm in proper position. This trip-device is adjustable lengthwise on said flange or the frame and it is preferably constructed of a single piece of sheet-metal bent 25 into such shape as to provide a base member 110 having longitudinal slots 111 through which screws are passed that take into said flange or frame, an upright or supporting-member 112 and an inwardly-directed trip- 30 member 113 separated throughout the greater portion of its length from said supporting-member by a slit 114 to form the spring-tongue 107. The front end of said trip-member has its upper face in the same 35 horizontal plane as the upper face of the rearward extension 36 of the bearing-block 35, so that when the slide-head 30 carrying said extension comes in contact with the front end of the trip-device 106 it occupies 40 the space normally left between the two. The purpose of this will now be explained. As shown in Figs. 4, 15, 16 and 17, the sheet of paper to be printed is laid upon the paper-support or positioner with its rear 45 marginal portion overhanging the rear edge of said support. As the carrier moves forward, the gripping-roller 90 and gripper 91 are separated owing to the toe or rider 105 having moved forward onto the trip-device 50 106, which causes the gripping-ledge 97 to move away from the gripping-roller and consequently the latter is carried above the overhanging portion of the sheet of paper while the gripping-ledge moves underneath 55 the same. As the carrier reaches the end of its forward movement, the toe or rider 105 drops over the elevated front edge of said trip-device and a flat spring 115, which is secured to the underside of the cross-bar 42 60 of the carrier and bears with its free end against the lower edge of the yoke 100, causes the gripping-ledge 97 to quickly rise and grip the paper between it and said gripping-roller. As soon as this is accomplished, 65 the carrier commences its rear movement, which causes the sheet of paper to be drawn rearward onto the type-form. During this rearward movement, the toe or rider 105 is held in contact with the upper face of the flange 18, and passes, during the initial portion of its return movement, under the spring-tongue 107 of the trip-device, which tongue is deflected upward thereby to permit said toe or rider to pass out under the rear end of said tongue. As said carrier approaches the end of its rearward movement, 70 the trip-arm 94 rides over the rear end of the trip-rail 25 and permits the torsion-spring around the spindle of the gripping-roller to expend its force for the purpose of 75 rocking said roller, which latter thereupon acts against the sheet of paper gripped between it and the gripping ledge and forces the paper forwardly during the last-portion of the rearward movement of the carrier. 80 The throw of the eccentrically-mounted roller is downward and consequently while rocking to eject the paper, the latter is brought closer to the type-form so that the drop of the sheet is reduced to the minimum. 85 The movement of the sheet forward while the carrier completes its rearward movement, is so timed relative to the travel of the carrier rearward, that when the carrier reaches a certain point in its rearward movement, the sheet to be printed does not move with reference to the length of the bed, and as it clears the gripping-ledge, it gravitates 90 to an exact position on the type-form. Owing to this action, the sheet will not float 100 in the air and finally land at uncertain points on the type-form.

When it is desired to throw the paper feeding-mechanism out of action, the slide-head 30 is moved rearward to bring the rearward extension 36 thereof against the front or elevated end of the trip-device 106 so that when the carrier is reciprocated the toe or rider 105 will ride up the spring-tongue 107 and onto the extension 36 of the bearing 110 block 35, thus holding the gripping-ledge 97 in lowered position until said toe or rider travels rearward over said spring-tongue; but before said toe or rider leaves said spring-tongue, the paper feeding-mechanism 115 will have been moved rearward out of range of the overhanging portion of paper on the paper-support or positioner.

By making the upper and lower faces of the toe or rider 105 convex, it will more 120 readily ride up the spring-tongue 107 and will also act more effectively in raising the rear end of said tongue when passing under it.

To the rear member 39 of the carrier, the 125 paper delivery-mechanism is applied. It consists of a rock-bar 116, a trip-arm 117, a trip-device 118, a paper-ledge 119 extending forward from the lower edge of the cross-bar 46, and a gripping-roller 120 coöperat- 130

ing with said paper-ledge and operatively connected with said rock-bar. The rock-bar 116 has its ends journaled in the sides 45 of said rear member of the carrier and it has 5 the trip-arm 117 secured to one end thereof. Said trip-arm has a laterally-extending stud or rider 121 adapted for co-action with the trip-device 118 which is similar in construction to the trip-device 106 hereinabove 10 scribed. The trip-device 118 is secured to the upper edge of one side of the frame or body 9 and has a spring-tongue 122 inclined rearward from an elevated point so that when the carrier is moved forward, the stud 15 or rider 121 rides up onto said spring tongue and causes the rock-bar 116 to rock in one direction and as said stud or rider reaches the elevated front end of said trip-device, it gravitates and causes said rock-bar to rock 20 in an opposite direction. This action takes place as the carrier approaches the end of its forward movement and simultaneously with the corresponding action of the toe or stud 105 of the paper-feeding mechanism. 25 During the initial portion of the rearward movement of the carrier, the stud or rider 121 passes underneath the spring-tongue 122 and causes the latter to be deflected upward.

Secured to the rock-bar 116 are two rearwardly and downwardly directed supporting-arms 123 in which is journaled the spindle of the gripping-roller 120. Surrounding said spindle at one end is a torsion spring 124 having one end secured to the 30 body of the roller and its opposite end to the adjacent supporting-arm. At its other end, said spindle has a lever 125 secured thereto to which is secured one end of a rod 126 which extends forward and has its other 35 end secured to a slide-bar 127 on one of the rods 40 connecting the front and rear members of the carrier.

The gripping-roller is preferably made in sections, as shown, and it is of sufficient 45 weight to normally rest upon the paper-ledge 119 so that the friction or resistance created thereby will prevent release of the power stored in the spring 124.

When the carrier reaches the end of its 50 rearward movement, the slide-bar 127 comes in contact with the fixed trip-arm 128 secured to the frame 9 of the machine and is therefore moved forward on said carrier. The action of said slide-bar is transmitted to 55 the lever 125 through the medium of the rod 126, which in turn causes the gripping-roller to rock.

Arranged transversely over the chase is a 60 paper support 129 upon which the rear end of the sheet of paper rests. This support is formed of a strip of metal having its ends bent downward, as at 130, 131, one of said downwardly bent ends being longer than the other. The long end 130 is clamped between 65 one side bar of the chase 22 and the

friction strip 24, while the short end rests upon the other side bar of said chase, as best shown in Fig. 24. The purpose of this support is to hold the rear marginal portion of the sheet of paper elevated above the type-form, or more particularly, above the furniture in the chase so that when the carrier moves forward and approaches the end of its movement, the paper-ledge 119 will pass underneath the rear marginal portion of the 70 printed sheet resting on the type-form, and simultaneously therewith the trip-arm 117 rides up the trip-device 118 so that the gripping-roller is elevated out of contact with the paper-ledge 119 and moves forward in a 75 plane above the rear end of the sheet of paper. When the trip-arm 117 passes over the elevated front end of said trip-device, the gripping-roller gravitates and grips the sheet of paper between it and said paper-ledge, drawing the paper rearward during the rearward movement of the carrier until the slide-bar 127 engages the fixed trip-arm 128 and causes said roller to rock, whereupon 80 the sheet is forced out from between said roller and said paper-ledge so that it may drop into the paper-receiver beneath. It will be noticed that when the slide-bar 127 is forced forward it causes the gripping-roller 85 to rock in one direction and the torsion spring 124 to be placed under tension, and as the trip-arm 127 rides up the trip-device 118, the gripping-roller is elevated free of the paper-ledge 119 and caused to rock in 90 the opposite direction by the action of said 95 spring.

While the carrier may be guided in its movements in any practicable manner, I prefer the use of guide-rollers 132 which are arranged in sets of three at each side of the carrier, two being in the same horizontal plane and rotatably mounted on stub-shafts 133 secured in the sides 41 of the carrier and the third being loosely positioned above and resting on the two supported on said shafts. 100 The guide-rollers travel on the yieldingly-supported tracks 14, while the upper roller rolls on said lower rollers and also rolls in contact with the flange 18 above. This construction assures an even impression and eliminates all play between the carrier and the frame. 110

Any suitable inking-device or medium may be employed to ink the type-form, but I prefer to employ an inked ribbon 134, 120 which is placed over the type-form and onto which the sheets of paper are to be placed so that the pressure of the impression-roller 47 against the paper will cause the imprint of the type to be made through said ribbon. Opposite ends of said ribbon are fastened to ribbon-rollers 135, 136, arranged at opposite ends of the bed 12, and the ribbon is wound from one roller onto 125 the other by means of suitable mechanism, 130

so that a gradual feeding of the ribbon over the type-form is obtained. The mechanism for feeding the ribbon may have a trip-arm 137 to be engaged by some part of the carrier and cause movement of said ribbon. As the feeding of the inked ribbon forms no part of my invention, I do not deem it necessary to enter into a detail description of the same.

10 Although I have, in describing the construction and relative arrangement of the several parts of the machine, made clear their operation, I will now proceed to give a brief step-by-step description of the operation:—Preparatory to printing, the gage-arm 83 and the gage-bar 86 are set to the width of the paper to be printed upon, the paper is stacked upon the paper-shelf 73, and the carrier moved slowly forward so 20 that the front end thereof will engage the rear edge of the paper-support or positioner 77 and move the same to the proper position for placing the sheets of paper relative to the feeding-mechanism so that the successive sheets placed upon said support or positioner will always be gripped by the gripper 91 and roller 90, at exactly the same points. The printing operation can then be started. The operator feeds the sheets of 30 paper from the stack on the paper-shelf 73 and carelessly drops them onto the support or positioner 77 between the gage-arms 83 and the gage-bar 86 which serve to properly position the sheets laterally. When operating the machine, the operator uses his left hand to rotate the operating wheel 65 and his right to place the sheets of paper upon said support or positioner, but when the machine is operated by power, he may 40 use either hand to place the paper on said support or positioner. When the carrier moves forward and approaches the end of such movement, the gripper 91 is moved away from the gripping-roller 90 so as to provide an intervening-space between the two. This action is caused by the oscillating yoke 100, to which said gripper is secured, having its toe or rider 105 travel onto 45 the trip-device 106. As the carrier approaches the end of its forward movement, said gripper and roller pass on opposite sides of the projecting marginal portion of the sheet to be fed to the type-form and in the event of said sheet projecting more than the exact distance intended for it, the gripper 91 strikes the edge thereof and forces it forward on the support or positioner. As 50 the toe or rider travels over the elevated front edge of the trip-device 106, the gripper rises to grip the sheet between it and its coöperating roller. This is done at the instant the carrier is ready for its rearward movement, and as it is moved rearward it carries the sheet with it and delivers it to the type-form. The trip-arm 94 passing

over the rear end of the trip-rail 25 causes the gripping-roller to rock and eject the sheet of paper from the feeding-mechanism, as and in the manner above specified. During said rearward movement of the carrier, 70 the impression-roller 47 is held out of printing-position by the trip-arms 51, 52, riding rearward over the trip-rails 26 but as said trip-arms pass over the rear ends of said rails, they are permitted to swing through 75 an arc of a circle. This movement of the trip-arms 51, 52, causes the eccentrically-mounted impression-roller to rock and move into printing position, so that it rides over the sheet of paper fed onto the type-form 80 with the proper pressure to cause it to receive the imprint of said form.

During the reciprocating movement of the carrier, caused by the gear-rack 60 of the driving-mechanism rotating the gear-wheel 85 59 in opposite directions which in turn causes the chain-wheels 55 around which the chains 54 pass to rotate in a similar manner, the operator will have had time to deposit a second sheet upon the paper-support or positioner, and when the carrier again approaches the end of its forward movement, the feeding-mechanism is placed into action to draw the second sheet onto the type-form, but before the carrier commences its rearward movement the impression-roller will have been moved out of printing-position by reason of the trip-arms 51, 52, passing over the front ends of the trip-rails 26 to permit them to swing 90 through an arc of a circle.

Simultaneously with the gripping of the sheet upon the support or positioner 77, the printed sheet on the type-form is engaged by the delivery-mechanism and drawn rearward to be delivered into the paper-receiver. This is done by the trip-arm 117 passing over the trip-device 118 and causing the gripping-roller 120 to be elevated so that it will pass over the rear end of the printed 105 sheet of paper while the paper ledge passes under the same. When the trip-arm 117 drops off the front elevated end of the trip-device 118, the roller 120 drops onto the paper to grip said end between it and said paper-ledge, and during the rearward movement of said carrier, it draws the printed sheet off the type-form. When the carrier approaches the end of its rearward movement, the slide-bar 127 engages the fixed trip-arm 128, causing the roller 120 to be rocked to eject the paper and permit it to drop into the paper-receiver.

Having thus described my invention, what I claim is,—

1. Two members coöperating to print upon a sheet of paper and a carrier movable back and forth over one of said members and supporting the other; combined with paper delivery-mechanism supported by said 130

- carrier and comprising two co-acting gripping members, one of said members having a curved gripping face and the other a flat gripping face.
5. Two members coöperating to print upon a sheet of paper and being relatively movable; combined with paper delivery-mechanism movable with one of said members and comprising two co-acting gripping-members, one being rotatable and having a curved gripping surface and the other being non-rotatable.
10. Two members coöperating to print upon a sheet of paper and a carrier movable back and forth over one of said members and supporting the other; combined with paper feeding-mechanism, supported by said carrier and comprising two co-acting gripping-members, one of said members being rotatable and the other being movable toward and from said rotatable member.
15. Two members coöperating to print upon a sheet of paper and being relatively movable; combined with paper feeding-mechanism movable with one of said members and comprising two co-acting gripping-members, one being rotatable and having a curved gripping-surface and the other being non-rotatable.
20. In a printing machine, the combination of a form-carrying member, a movable impression member, an inking device, a reciprocating paper feeding mechanism movable with said impression roller and placed into action after times of printing, said feeding mechanism being adapted to carry the sheets of paper onto said form carrying member preparatory to printing.
25. In a printing-machine, the combination of a form-carrying member, an impression-member, means for causing said impression member to travel in contact with said form-carrying member, paper feeding-mechanism traveling with said impression-member and adapted to carry the sheets of paper to said form-carrying member and means to cause the feeding-mechanism to release the sheet of paper when positioned for printing.
30. Two members coöperating to print upon a sheet of paper; combined with paper feeding-mechanism comprising an eccentrically-mounted roller, a gripper coöperating with said roller, and means to give said roller a slight rotary motion at a certain time in the act of feeding a sheet of paper.
35. Two members coöperating to print upon a sheet of paper; combined with paper feeding-mechanism comprising a roller mounted to permit of rotary movement, a flat gripper coöperating with said roller to grip a sheet of paper, and means to cause said roller to rotate only at a certain time in the act of feeding the paper.
40. In a printing-machine, the combination with two members coöperating to print upon a sheet of paper, of paper-carrying mechanism comprising two gripping-members, one movable relative to the other to grip a sheet of paper and one rotatable only at intervals to eject the sheet from between said gripping-members.
45. In a printing machine, the combination of a form-carrying member, the combination of a form-carrying member, an impression member coöperating therewith to print upon a sheet of paper, and paper feeding mechanism traversing said form-carrying member and adapted to release the sheet of paper after printing, said mechanism embodying means acting when releasing the sheet of paper to remove the same in a direction opposite to that in which it is traveling.
50. In a printing-machine, the combination of a form-carrying member, an impression-member, traveling paper feeding-mechanism comprising a gripper movable toward and from said form-carrying member and a roller against which said gripper is adapted to move to grip a sheet of paper, and means to cause said roller to rotate at a certain point in the movement of said feeding mechanism.
55. In a printing-machine, the combination of a form-carrying member, an impression-member, traveling paper feeding-mechanism comprising a gripper movable toward and from said form-carrying member and a roller against which said gripper is adapted to move to grip a sheet of paper, and means to cause said roller to rotate at a certain point in the movement of said feeding mechanism.
60. In a printing machine, the combination of a form-carrying member, an impression-member, traveling paper feeding-mechanism comprising a gripper held to said carrier and vertically movable thereon, a gripping-roller rotatably mounted in said carrier and coöperating with said gripper to grip a sheet of paper, and means to actuate said gripper and said gripping-roller at certain points in the movement of said carrier.
65. In a printing-machine, the combination of a form-carrying member, a traveling-carrier movable relative thereto, an impression-roller mounted in said carrier and movable into and out of printing position, a gripper held to said carrier and vertically movable thereon, a gripping-roller rotatably mounted in said carrier toward which said gripper is adapted to move to grip a sheet of paper between the two at a predetermined point in the movement of said carrier, a trip-arm secured to said roller, and a riding surface over which said arm travels and over the end of which it will pass to cause said roller to rotate at a second predetermined point.

- point in the movement of said carrier, as and for the purpose described.
15. In a printing-machine, the combination with a flat form-carrying member, a traveling-carrier, and an impression-member on said carrier movable toward and from said form-carrying member, of a gripping-device also on said carrier and comprising a pair of paper gripping-members, a trip-device on said form-carrying member, a trip-arm connected with said gripping-device and adapted to engage said trip-device to cause said gripping-device to grip a sheet of paper, and means to cause the sheet of paper to be released from said gripping-device. 5 70
16. In a printing-machine, the combination with a flat form-carrying member, a traveling-carrier, and an impression-member on said carrier, of a gripping-device also on said carrier and comprising a vertically-movable gripper having a horizontal paper-ledge, a roller above said paper-ledge having its spindle journaled in said carrier, a spring surrounding said spindle and having one end secured to said roller and its other end to said carrier, an oscillating element on said carrier supporting said gripper, a trip-device on the form-carrying member in the path of said oscillating member and serving to cause said gripper to move toward and from said roller at certain points in the movement of said carrier, and means to cause said roller to rotate at a certain point in the movement of said carrier. 20 85
17. In a printing-machine, the combination with a flat form-carrying member, a traveling-carrier, and an impression-member on said carrier, of a gripping-device also on said carrier and comprising a vertically-movable-gripper having a horizontal paper-ledge, a roller above said paper-ledge having its spindle journaled in said carrier, a spring surrounding said spindle and having one end secured to said roller and its other end to said carrier, means to cause said gripper to move vertically toward and from said roller at certain points in the movement of said carrier, a trip-arm on the spindle of said roller, and a trip-rail on said form-carrying member against which said trip-arm bears and over the end of which it passes, said spring causing said roller to rotate in one direction when said trip-arm passes over the end of said trip-rail and said trip-arm causing said spring to be placed under tension and said roller to rotate in the opposite direction when passing onto said trip-rail. 25 95
18. In a printing-machine, the combination with a flat form-carrying member, a reciprocating carrier, and an impression-member on said carrier coöperating with said form-carrying member, of gripping-mechanism including a movable part also on said carrier, and a trip-device on said form- 30 100
- carrying member in the path of the movable part of said gripping-mechanism, said trip-device including an inclined member over which said movable part travels when said carrier moves in one direction and under which it travels when the carrier moves in the opposite direction. 35 105
19. In a printing-machine, the combination with a flat form-carrying member, a reciprocating carrier, and an impression-member on said carrier coöperating with said form-carrying member, of gripping-mechanism including a movable part also on said carrier, and a trip-device on said form-carrying member in the path of the movable part of said gripping-mechanism, said trip-device having an inclined spring tongue over which said movable part is adapted to travel when the carrier moves in one direction and under which it travels when the carrier moves in the opposite direction, said tongue being deflected upward by said movable part when traveling under it. 40 110
20. In a printing-machine, the combination with a flat form-carrying member, a reciprocating carrier, and an impression-member on said carrier coöperating with said form-carrying member, of gripping-mechanism including a movable part also on said carrier, a trip-device on said form-carrying member in the path of the movable part of said gripping-mechanism, said trip-device comprising an inclined member onto and over the elevated end of which said movable part is adapted to travel when said carrier moves in one direction and underneath which said movable part is adapted to travel when the carrier moves in the opposite direction, and means to prevent said movable part of the gripping-mechanism dropping over the elevated end of said trip-device. 45 115
21. In a printing-machine, the combination with a flat form-carrying member, a reciprocating carrier, and an impression-member on said carrier coöperating with said form-carrying member, of gripping-mechanism including a movable part also on said carrier, a trip-device on said form-carrying member in the path of the movable part of said gripping-mechanism, said trip-device comprising an inclined member onto which and over the elevated end of which said movable part is adapted to travel when said carrier moves in one direction and underneath which said movable part is adapted to travel when the carrier moves in the opposite direction, and a slide-block having its upper face in the same plane as the elevated end of said trip-device and movable toward and from said trip-device to permit said movable part of the gripping-mechanism to drop over the elevated end of said trip-device or to compel said movable part to pass onto said slide-block. 50 120
22. In a printing-machine, the combina- 55 125
- 60 130

tion of a form-carrying member, a movable-carrier, a paper-positioner movable on said form-carrying member and automatically adjustable to proper position when in the 5 path of said carrier, an impression-member on said carrier, and paper feeding-mechanism adapted to remove the sheets from said paper-positioner and feed them to said form-carrying member.

10 23. In a printing-machine, the combination of a form-carrying member, a carrier movable over said form-carrying member, an impression-member on said carrier adapted to cause a sheet of paper placed on said 15 form-carrying member to be printed, and paper delivery-mechanism also on said carrier and spaced from said impression-member, said delivery-mechanism comprising a paper-ledge and a gripping-roller rotatable 20 and movable toward and from said paper-ledge.

24. In a printing-machine, the combination of a form-carrying member, an impression-member, and paper delivery-mechanism 25 spaced from said impression-member, said delivery-mechanism comprising a paper-ledge, a rock-bar, arms secured to said rock-bar, a gripping-roller journaled in said arms, a lever secured to the spindle of said 30 roller, and means for causing said lever to move in an arc of a circle.

25. In a printing-machine, the combination of a form-carrying member, an impression-member, and paper delivery-mechanism 35 spaced from said impression-member, said delivery-mechanism comprising a paper-ledge, a rock-bar journaled in said carrier, a pair of arms secured to said rock-bar, a gripping-roller journaled in said arms 40 and movable toward and from said paper-ledge, a lever secured to the spindle of said roller, a slide-bar, a stop on said form-carrying member against which said slide-bar strikes, and a rod connecting said slide-bar 45 with said lever.

26. In a printing-machine, the combination of a form-carrying member, an impression-member, and paper delivery-mechanism also on said carrier, said delivery-mechanism

comprising a paper-ledge, a gripping-roller 50 movable toward and from said paper-ledge, a spring acting to rotate said roller in one direction and held under tension when said roller is in contact with said ledge, said spring acting to rotate said roller in one 55 direction when the latter is moved from said paper-ledge, and means to rotate said roller in the opposite direction so as to place said spring under tension, the whole acting to grip a printed sheet and deliver the same. 60

27. In a printing-machine, the combination of a form-carrying member, an impression-member, paper delivery-mechanism comprising two gripping-members normally in contact, one of said members having rolling 65 contact with the other, a pivoted trip-arm, connection between said trip-arm and one of said gripping-members, and a trip-device on said form-carrying member having an inclined tongue above and under which a 70 portion of said trip-arm rides.

28. In a printing-machine, the combination of a form-carrying member, an impression-member adapted to cause a sheet of paper placed on said form-carrying member 75 to be printed, a transversely-disposed fixed paper-support positioned over said form-carrying member to hold one end of the paper out of contact with parts beneath it, and paper delivery-mechanism having gripping-members passing above and beneath 80 said end of the paper to grip the same and remove it from said form-carrying member.

29. In a printing machine, a paper-carrying device comprising two coöperating members, one at least being cylindrical, and means for actuating the cylindrical member to cause it to release the paper from said device by rolling in contact therewith, said cylindrical member being otherwise held 90 against rotation.

In testimony whereof, I have affixed my signature in the presence of two subscribing witnesses.

CHARLES E. ADAMSON.
